UNITED STATES PATENT OFFICE.

FREDERICK W. HOCHSTETTER, OF NEW YORK, N. Y., ASSIGNOR TO PAUL M. PIERSON,
OF SCARBORO-ON-THE-HUDSON, NEW YORK.

PROCESS FOR RESTORING BLEMISHED MOVING-PICTURE FILMS.

1,192,424.

Specification of Letters Patent. Patented July 25, 1916.

No Drawing.

Application filed June 20, 1913. Serial No. 774,864.

To all whom it may concern:

Be it known that I, FREDERICK W. HOCHSTETTER, a subject of the Emperor of Germany, and a resident of New York, county and State of New York, have invented a certain new and useful Process for Restoring Blemished Moving-Picture Films, of which the following is a full, clear, and exact specification.

10 This invention relates to a process for treating moving picture films which have become impaired by use.

In my applications for compositions of matter for restoring the pictures on films, 15 Serial Number 732,465, Serial Number 770,177, and Serial Number 771,689, I employ an oil, or a fatty base mixed with one or more other ingredients to form an emulsion which is adapted to be applied on the 20 film to restore its flexibility and for removing from the scratches and from the photography of the pictures thereon all particles of dust and foreign substances which impair the transparency of the film during its 25 transmission through a projecting machine. In instances these forms of blemishes of the film may be effectually removed by employing a single fat, or a single oil, thereby dispensing with the use of the other ingredients 30 of the above referred to compositions of matter. These advantages are attained by utilizing a mineral oil or an animal fat, or vegetable oil, such as petrolatum, paraffin, spermaceti, beeswax, oil of petroleum, oil of 35 turpentine, lard oil, benzin, naphtha, olive oil, cotton seed oil, oil of sweet almonds, or the like, all of which should preferably be of a purified quality when used.

In practice when a fat is used it is preferably melted under the influence of heat to a semi-liquid state, or to a consistency whereby the substance may be conveniently applied upon the surface of a film through the medium of a pad, brush, or other suitable 45 means, or when an oil is employed it is similarly applied upon the surface of the film until a coating is formed thereon. By the employment of a buffer, or pad of any desired type the coating is subjected to sufficient friction to soften the texture of the film and to force the substance into the crevices of the scratches thereof. The foreign substance collected on the film will thereby be absorbed by the cleaning ma-

terial, and by the use of a pad of chamois 55 skin, cloth, cotton, or other soft material all of the surplus coating is removed from the film which in turn will clear the high lights and shadows of the pictures as well as freeing the scratches in the film of all of the foreign 60 matter. When both surfaces of the films have been coated with the oily material which slightly softens the surface emulsion thereon, a portion of the oily material is removed as has been stated, thereby removing 65 the foreign matter collected on the films. The surfaces are then rubbed and buffed to remove the final surplus oily-coating and particularly to burnish the softened emulsion thereby closing the scratches in such 70 manner that the surfaces of the film are restored to their original condition. Moving picture films which become so blemished as to be practically worthless after being used a limited number of times may thus be restored and utilized for many exhibitions of the pictures thereon.

Having thus described my invention, I claim as new and desire to secure by Letters Patent:—

1. The process of restoring blemished moving picture films, which consists in coating said film with an oily material capable of softening the surface thereof; rubbing and buffing the surface so treated to first 85 clean and then remove the scratches therefrom; and then removing the oily material from the surface of the film.

2. The process of restoring blemished moving picture films which consists in coating said film with an oily material capable of softening the surface of the emulsion thereon; then removing a portion of said oily material and the foreign matter collected thereby; then rubbing and buffing the 95 surface of the film to remove the surplus oily coating and burnish the softened emulsion to close the scratches in such manner that the surfaces of the film are restored to their original condition.

This specification signed and witnessed this nineteenth day of June, A. D. 1913.
